UNITED STATES PATENT OFFICE.

ROBERT G. FISHEL, OF CHICAGO, ILLINOIS.

DESIGN FOR A COMBINED DISPLAY AND VENDING CABINET.

Application filed July 5, 1927. Serial No. 22,660. Term of patent 3½ years.

To all whom it may concern:

Be it known that I, ROBERT G. FISHEL, a citizen of the United States, residing at Chicago, county of Cook, and State of Illinois, have invented a new, original, and ornamental Design for a Combined Display and Vending Cabinet, of which the following is a specification, reference being had to the accompanying drawing, forming a part hereof, in which—

Figure 1 is a view of the article in perspective; and

Fig. 2 is a view in side elevation.

I claim:

The ornamental design for a combined display and vending cabinet as shown.

ROBERT G. FISHEL.
